FIRETRAP FOR PROJECTION MACHINES

Albert H. Reynolds, Dallas, Tex.

Application July 8, 1946, Serial No. 682,096

3 Claims. (Cl. 88—17)

1

This invention relates to fire traps for motion picture projection machines, and more particularly to a device for cutting the film and sealing the openings between the projector and the film magazines.

It is an object of this invention to provide a device for severing the film and sealing off the openings between the projector and the film magazines, upper and lower, when a fire develops in the projection or sound head.

Another object of this invention is to provide a device which releases a knife to cut the film between the film magazine and the projector when the temperature in the projector reaches a predetermined degree, and it has been found that a temperature of 110 degrees Fahrenheit should not be exceeded in the projector.

Another object of this invention is to provide a device for trapping a fire in the projection head which may be readily adapted to various sized projectors and film magazines and which may be readily installed on or incorporated in any or all present existing machines and need not be a device necessarily installed only at the time of manufacture of the projector or magazine.

Still another object of this invention is to provide a fire trap of the kind to be hereinafter described which may be readily manufactured and sold at an economical price, and in which the installation costs are practically negligible.

With the above and other objects in view, my invention consists in the arrangement, combination and details of construction disclosed in the drawings and specification, and then more particularly pointed out in the appended claims.

In the drawings,

Wherein similar reference characters designate similar parts throughout the respective views,

Figure 1 is a side elevation, partly broken away and partly in section, of a projector equipped with a fire trap constructed according to an embodiment of my invention.

Figure 2 is a side elevation, partly broken away and partly in section, of my fire trap installed in an upper magazine,

Figure 3 is a side elevation, partly broken away and partly in section, of my fire trap installed in a lower film magazine,

Figure 4 is a section taken on the line 4—4 of Figure 5,

Figure 5 is a top plan view, partly broken away, with the top cover removed,

Figure 6 is a vertical section taken on the line 6—6 of Figure 5.

Referring to the drawings, the numeral 10 designates generally a motion picture projection machine having a sound head 11 fastened to or formed on the lower end thereof, and is equipped with the conventional type of upper and lower film magazines 12 and 14 respectively.

2

The numeral 15 designates generally a fire trap constructed according to an embodiment of this invention and is so constructed and designed that it may be secured on a motion picture projector

5 10 between the projector 10 or sound head 11 and the magazines 12 and 14 as shown in Figure 1, or may be installed or incorporated within the magazines 12 and 14 as shown in Figures 2 and 3. The type of installation is optional for a user, 10 depending on his particular desires or upon the particular equipment on which this fire trap 15 is to be installed. The only difference in the installations is the location and means of attachment which may be varied to any circumstances 15 and do not form a part of this invention inasmuch as the same fire trap 15 may be used irrespective of the installation. No particular means of securing this fire trap 15 are shown in the drawings as it is considered that this fire trap 15 20 may be frictionally held in position between the magazine and projector body by the magazine attaching clamps in Figure 1 not shown, or may be fixed by bolts or rivets or any other suitable attaching means not shown, in Figures 2 and 3.

25 The fire trap 15 comprises a relatively thick metal segmental arcuate body plate 16, an upper cover plate 17, a lower cover plate 18, and a knife blade 19 slidably carried between the body plate 16 and upper cover plate 17.

30 The body plate 16 is formed of a rectangular segmental arcuate strip of relatively thick metal and is formed on the upper concave side with a large rectangular recess 20 near one end thereof in which the knife 19 is adapted to be slidably 35 engaged. A pair of parallel longitudinally extending slots 21 are formed in the plate 16 and extend from one end well into the recess 20. The plate 16 is further formed with a rectangular opening 22 which opens vertically from the recess

40 21 and a side opening or cut out 24 communicating with the opening 22 and recess 21 whereby the film may pass through the opening 22 when the projector is in operation and through the opening 24 when the fire trap 15 is being installed 45 or removed.

The knife 19 is formed of a substantially rectangular body having a beveled knife edge 25 on one end thereof and a pair of rearwardly extending lugs 26 on the opposite end. The blade 19 is 50 slightly shorter in width than the recess 20 and considerably shorter in length whereby it may be slidably therein. A pair of coiled springs 27 are carried in the slots 21 and engage the end of the plate 16 at one end and engage the blade 19 at the other end by engaging over the rearwardly projecting lugs 26.

The upper cover plate 17 is formed of an elongated sheet of metal of substantially the same 55 dimensions as the plate 16 and is formed with

openings 28 and 29 which register with openings 22 and 24 of plate 16 for admitting the film 30.

The lower cover plate 18 is formed of an elongated sheet of metal of the same width as the plates 16, 17 and is formed with upstanding flanges 31 on each end thereof which are adapted to be attached to the ends of plate 16 by screws 32 or other suitable attaching means, while the upper cover plate 17 is secured to plate 16 by flush screws 34 through the upper surface of the plate 17.

The knife 19 is further formed with a detent 35 on the lower convex surface in which the upper end of a trigger or belt 36 is adapted to be engaged.

For holding the knife 19 in retracted position for normal operation of the projector 15, there is provided a renewable fuse 40 which is secured to the plate 16 and extends through the walls of the projector and through the magazine supporting wells 37. The fuse 40 consists of a tubular body section 41 threaded externally along its length as at 42 and is provided at its inner end with an annular flange 44 which is adapted to engage the inner recessed surface of the recess 20 for supporting the fuse 40 therefrom. The fuse body 41 extends outwardly from the plates 16 and 18 and a nut 45 about the body 41 clamps the fuse 40 onto the plates 16 and 18.

Enclosed and slidably within the body 41 is a cylindrical trigger member 36 having a rounded knife engaging end and a reduced diameter outer end 46. Also slidable in the body 41 at the opposite end is a cylindrical plug engaging member 47 having a reduced diameter tubular inner end portion 48. The reduced end 46 of the trigger 36 slidably engages in the reduced tube 48 and a spring 49 therein constantly urges the trigger 36 upwardly into engagement with the blade 19. A second spring 50 about the trigger 36 and reduced tube 48 engages the inner end wall of the body 41 at its inner end and the rear side of the member 47 at its outer end for constantly urging the member 47 outwardly thereby releasing the trigger 36.

For holding the trigger in engagement with the knife 19, I have provided a plug 51 which is threadable on the outer end of the body 41. The end wall of the plug 51 is formed with an annular opening 52 through which the reduced outer end 54 of member 47 may be slidably engaged.

A pair of oppositely disposed substantially U-shaped levers 55 are pivotally connected to the outer side of the plug 51 in such a manner that one arm of each lever 55 extends over the opening 52 and the end 54 of the member 47 engages these arms which arms retain the member 47 in retracted position. The other arms of the levers 55 are connected to each other by a fusible element 56 for holding the levers 55 in operative position. When an excessive temperature is reached the fusible element 56 separates and the levers 55 are pivoted permitting the member 47 to be urged to the outer end of the body 41, thus reducing the spring tension on the trigger 36 and permitting the knife 19 to separate the film 30 and seal the opening 22. In this condition the reduced portion 54 protrudes through the plug 51. To restore the projector to operative condition a new plug 51 must be installed and the knife 19 moved to retracted position.

In all types of installations it is desirable that the body 41 be of considerable length in order to support the fusible plug 51 within the projector body 10 or within the sound head 11 where the fire is usually originated.

I do not mean to confine myself to the exact details of construction herein disclosed, but claim all variations falling within the purview of the appended claims.

Having thus described my invention, what I desire to claim is:

1. A fire trap for attachment to a motion picture projector and magazine comprising a recessed guide plate for attachment between the projector and magazine, a spring-pressed knife slidable in said plate for severing the film and closing the opening between the projector and magazine, a tubular body carried by said plate, a trigger supporting tube slidable in said body, a spring-pressed trigger slidable in said trigger supporting tube engaging said knife for normally holding said knife in retracted position, an apertured plug removably carried by an end of said body opposite from said trigger, a portion of said 10 supporting tube extensible through said plug for releasing the spring tension of said trigger, a pair of levers rockably carried by said plug, and fusible means connecting said levers together for restraining said trigger supporting tube in said body.

2. A fire trap for a motion picture projector and magazine comprising a recessed guide plate between said projector and magazine, a spring-pressed knife slidable in said plate for severing the film and closing the opening between the projector and magazine, a tubular trigger and fuse supporting body on said plate extending into said projector, a trigger, a trigger supporting member slidable in said body, spring means between said trigger and trigger supporting member biasing said trigger into restraining engagement with said knife, spring means urging said trigger supporting member into trigger spring tension releasing position, a plug on said body, and fusible means carried by said plug restraining said trigger supporting member in trigger spring tensioning position.

3. In a fire trap for a motion picture projector and magazine having a spring-pressed knife slidably supported between said magazine and projector for severing the film and closing the opening between the projector and magazine, a recessed knife guide member, a tubular trigger housing carried by said guide member and extending into said projector, a spring-pressed trigger supporting member slidable in said housing, and biased downwardly therein, a spring-pressed trigger carried by said supporting member and extending from one end of said housing for engagement with said knife, an apertured plug threadably carried by the other end of said housing, said trigger supporting member extensible through said apertured plug for releasing the tension of said spring-pressed trigger, a pair of rock levers carried by said plug restraining said supporting member in trigger tensioning position and fusible means holding said rock levers in engagement with said trigger supporting member.

ALBERT H. REYNOLDS.
